UNITED STATES PATENT OFFICE.

CLINTON F. BLAKE, OF PORTLAND, OREGON.

LUGGAGE-RACK.

1,349,938.

Specification of Letters Patent. Patented Aug. 17, 1920.

Application filed September 24, 1919. Serial No. 328,077.

To all whom it may concern:

Be it known that I, CLINTON F. BLAKE, a citizen of the United States, and a resident of Portland, county of Multnomah, State 5 of Oregon, have invented certain new and useful Improvements in Luggage-Racks, of which the following is a specification.

My invention relates to luggage racks in general, and particularly to such racks as 10 are adapted to be secured to the running boards of automobiles for the purpose of holding luggage thereon, and is so illustrated in the accompanying drawings, which are a part of this application for Letters 15 Patent.

The object of my invention is to provide a luggage rack of extremely simple construction and few parts, of great strength, and of easy and quick adjustability and attachment to the running board.

I accomplish the above object by means of the construction illustrated in said drawings, like characters indicating like parts throughout the several views thereof, and 25 in which:

Figure 1 is a perspective view of an automobile with my invention in place thereon.

Fig. 2 is a side elevation of my device.

Fig. 3 is a perspective view of the clamp 30 used to secure my device to the running board.

Fig. 4 is an end elevation of the subject matter of Fig. 3.

Figs. 5, 6, 7, 8 and 9 are perspective views 35 of details of the clamp.

In general my device consists of an extensible member in the form of the well known lazytong, certain members thereof being of extra strength, a clamp pivotally 40 secured upon the end of each of said extra strength members by suitable journals upon said clamp, and means to permanently adjust said clamps to the thickness of the running board.

45 The rack is made of thin strips of metal 10 diagonally disposed (when the rack is extended for use), and each pivotally connected to the adjacent strip.

To give the greatest strength to the rack 50 it is desirable to support the same at certain of the uppermost and also certain of the lowermost points thereof, and in order to make the rack as light as possible, said supporting must be accomplished with the

least material possible. I accomplish this 55 by constructing certain of the diagonal members of the rack of material considerably heavier than the members 10, as shown at 11, said members 11 being pivotally connected to the adjacent members 10, as shown 60 in Figs. 1 and 2.

To secure the rack to the running board of the automobile I provide clamps upon the lower ends of each of the members 11, and as the members 11 assume various angles as the rack is more or less extended, these clamps are necessarily pivotally attached to their respective members 11.

In order to render the rack of great stiffness transversely thereof, I turn the lower 70 end of each of members 11 normal thereto, as shown in Fig. 3, thus forming a foot 11^a which may be journaled within the clamp, and which foot will form a sufficiently long lever arm to render the rack transversely 75 secure.

It is necessary to have the clamp adjustable to running boards of various thicknesses, and also it is desirable to have the clamp quickly and easily attachable to the 80 running board, and this I accomplish as follows.

The clamping jaws are formed of two pieces, an upper T shaped jaw 12 and a lower L-shaped jaw 13, shown in detail in Figs. 5 85 and 6 respectively, adapted to contact with the running board above and below the same respectively. To make said jaws adjustable to various thicknesses of running boards I provide the upper jaw 12 with two bolt 90 holes 14, and the lower jaw 13 with a slot in one arm thereof adapted to register with bolt holes 14 in jaw 12, said jaws being secured together by bolts 17 passing through said bolt holes and said slot, thereby rendering the jaws adjustable to running boards of various thicknesses by sliding the bolts 17 within slot 16 until the distance between the jaws is just sufficient to allow the running board to pass therebetween.

Having thus adjusted the jaws to the running board thickness, it is necessary to provide means to clamp the same upon the running board, and I accomplish this by pivoting an eccentric clip 18 upon upper jaw 105 12 in such a manner that rotation of the clip will cause the eccentric portion 18^a thereof to exert pressure upon the upper

- surface of the running board, and thereby securely clamp the same between said eccentric portion of the clip 18 and the lower jaw 12.
5. To prevent the clip 18 from wearing slots in the upper surface of the running board I provide a wearing strip therefor, in the form of a thin strip of metal adapted to lie between said clip 18 and the running board, 10 and to receive the pressure of the clip thereupon, said strip 19 being thin enough to yield under the pressure of the clip and thereby clamp the running board, said strip 19 being provided with an arm 20 normal 15 thereto adapted to be secured, as by rivets, to the upper jaw 12, as shown in Fig. 3.

By means of this construction of the clamp, the jaws thereof may be permanently adjusted to the thickness of the running board by means of the bolts 17, and thereafter it is only necessary to slip the jaws in place upon the running board and press downward upon the respective clips 18, to securely attach the rack to the running 25 board.

To pivotally mount the above described clamping device upon the ends of the respective members 11 I provide the upper jaw 12 with an arm 12^a normally turned 30 upon the end thereof and having therein an orifice 12^b adapted to form a bearing for the end of the foot 11^a of the member 11, as shown in Figs. 3 and 5. At the opposite end of foot 11^a I provide a semicircular 35 U shaped clip 21, shown in detail in Fig. 7, having bolt holes therein adapted to register with bolt holes 14 in upper jaw 12, and to receive bolts 17 therein, as shown in Figs. 3 and 4, said clip encompassing the foot 11^a 40 and forming a bearing therefor when in place. The clamp is held in place by slightly heading over the end of the foot 11^a after passing the same through the orifice 12^b.

My device may be made of any size and 45 constructed of any materials deemed convenient and suitable for a device of this character, and while I have illustrated and described a form of construction and arrangement of parts found desirable in materializing my invention, I wish to include 50 in this application for Letters Patent all mechanical equivalents and substitutes that may fairly come within the scope and purview of my invention as defined in the appended claims.

Having disclosed my invention so that others may be enabled to construct and to use the same, what I claim as new, and desire to secure by Letters Patent is:

60. 1. In a luggage rack, a plurality of clamps each consisting of a pair of parallel jaws, means to adjust the distance between said jaws and to positively secure the same at the desired distance one from the other, a

clamping device secured to one of said jaws, 65 and bearings upon the other of said jaws; in combination with a rack of lazy tong construction consisting of a plurality of flat bars diagonally disposed, a plurality of round bars diagonally disposed, feet upon 70 each of said round bars normal thereto and adapted to be mounted within said bearings of said clamps.

2. In a luggage rack, a plurality of adjustable clamps each consisting of a pair 75 of jaws, means to adjust the distance between said jaws, a clamping device upon one of said jaws, and bearings upon the other of said jaws; in combination with inclined members having normally turned feet mounted within the said bearings of the respectively adjacent clamp, and a rack of lazy tong construction, certain uppermost and lowermost pivotal points of said rack being connected to the respective one of 80 said inclined members.

3. In a luggage rack, an L shaped jaw member having a slot in the vertical leg thereon; a T shaped jaw member having orifices in the vertical part thereof; bolts 90 adapted to pass through said orifices and said slot to secure said jaw members together in any desired relative adjustment; a clamping device upon said T shaped jaw member; bearings upon said T shaped jaw 95 member; a diagonally disposed supporting member; a foot turned normal to said supporting member upon the lower end thereof and adapted to be mounted within said bearings; and an extensible rack pivotally 100 connected to said supporting member.

4. In a luggage rack, a pair of relatively adjustable jaws; a clamping device upon one of said jaws; journals upon each end of one of said jaws; a diagonal supporting member; an elongated foot turned normal to said supporting member upon the lower end thereof and mounted within said bearings; and an extensible rack supported upon said 105 supporting member.

5. In a luggage rack, a pair of relatively adjustable jaws, one of said jaws having a vertically disposed slot therein and the other of said jaws having two orifices therein each registering with said slot; a U shaped 115 clip having two orifices therein registering with said orifices in said jaw; bolts adapted to pass through both their respective orifices in said clip, their respective orifices in said jaw, and through said slot, thereby securing said jaws and said clip together; a bearing upon the extremity of the jaw having thereon said orifices; a clamping device upon one of said jaws; a diagonally disposed round bar; a foot turned normally upon the lower 120 end of said bar and mounted in said clip and said bearing; and an extensible rack secured to said round bar.

6. In a luggage rack, a plurality of clamps each consisting of a pair of relatively adjustable jaws, a clamping device upon one of said jaws, and bearing members spaced apart upon the other of said jaws; in combination with a lazy tong frame having certain members thereof extended below said frame and the lower ends of said extended

members turned normal thereto and mounted within said bearings.

10

In witness whereof I claim the foregoing as my own I hereunto affix my signature at Portland, county of Multnomah, State of Oregon, this 17th day of Sept., 1919.

CLINTON F. BLAKE.
